UNITED STATES PATENT OFFICE.

GEORGE J. VON GLAHN, OF BROOKLYN, NEW YORK.

PIPE FITTING.

Application filed August 22, 1921. Serial No. 494,223.

To all whom it may concern:

Be it known that I, GEORGE J. VON GLAHN, a citizen of the United States, residing at Brooklyn, in the county of Kings and State 5 of New York, have invented certain new and useful Improvements in Pipe Fittings, of which the following is a specification.

This invention has relation to sink fittings, and has for an object to provide an 10 improved elbow coupling adapted to receive the threaded extension of a faucet when the latter is to be mounted on a sink, said elbow coupling having means to engage the sink and to grip the wall of the sink between 15 said means and the flange of the faucet whereby the faucet and sink are held against relative movement, and to perform other purposes as will be presently obvious.

Another object of the invention is to 20 provide an improved coupling having the characteristics above set forth and in addition thereto being designed for use in connection with two different kinds of faucets, namely, those of the turn plug type having 25 a handle operating in a horizontal plane, and those of the cone valve type having a handle operating in a vertical plane, the coupling being designed to resist strain placed upon the faucet by operation of the 30 handle in either direction preventing dislodgment of the faucet relative to the sink.

In addition to the foregoing this invention comprehends improvements in the details of construction and arrangement of 35 parts to be hereinafter described and particularly set forth in the appended claims.

In the accompanying drawings in which 40 similar and corresponding parts are designated by the same characters of reference throughout the several views in which they appear.

Figure 1 is a view in side elevation, partly 45 in section of a faucet and fragments of a sink wall showing the embodiment therein of my invention.

Figure 2 is a view in perspective of my improved elbow coupling.

Figure 3 is a view of a slightly modified 50 form of elbow coupling.

Figure 4 is a view in side elevation of another form of faucet with the corresponding 55 form of my invention applied thereto.

With reference to the drawings, 10 indicates the back wall of a sink having an 55 opening 12 in which the threaded extension 13 of a faucet 14 extends the latter having

a flange 15 which engages the front surface of the said wall. It will be noted that the opening 12 is larger in diameter than the extension 13 or smaller than the flange 15, 60 so as to permit adjustments of the faucet relative to the opening 12 when making connection with the plumbing, since the faucet may not always be located centrally of the openings 12. The stand pipe of the 65 plumbing system is shown at 16 and threadedly engaged thereupon is an elbow 17 which also receives the threaded extension 13. As shown in Figure 1 a lug 18 is formed upon the outer side of the coupling 70 to engage the rear surface of the sink wall and another lug 19 is provided to similarly engage the sink wall, said last mentioned lug being located upon the inner side of the coupling and between the ends thereof as 75 shown more clearly in Figure 3. These lugs are formed integrally with the elbow during the process of casting. The faucet is rotated so as to screw the extension 13 tightly into the coupling and it will be seen 80 that the sink wall is tightly gripped between the flange 15 and the lugs 18 and 19. In this manner the sink and faucet are held immovably together and may not be displaced while subject to ordinary use. Also 85 the stand pipe 16 is thus enabled to afford an additional support for the sink. The faucet shown in Figure 1 is of the type embodying a vertically reciprocable cone valve 90 and it will be obvious that as the same is actuated a vertical strain is placed upon the entire faucet. Owing to the facts that the lugs 18 and 19 are in vertically aligned 95 relation this movement of the faucet is effectually resisted.

I have illustrated in Figure 3 a modified form of coupling consisting of a vertical portion 20 which is formed with a right angular bend at its upper end terminating in a flanged internally threaded portion 22 100 designed to receive the threaded extension 13 of the faucet. This form is employed where the stand pipe is of lead instead of iron and in the form shown in Figure 1. In the case of the lead stand pipe a wipe 105 joint is effected between the stand pipe and the portion 20. In this instance I have shown a pair of lugs 23, formed integrally with the flanged portion 22 and the side of the portion 21 extending along the latter 110 for a portion of its surface. The lugs are diametrically opposed, in radial alignment.

and in a horizontal plane. This type is employed where the faucet is of the rotatable turn plug type in which the effort of turning the valve results in a strain tending 5 to move the faucet in a horizontal plane. Such movement being effectually resisted by the horizontal position of the lugs 23.

Thus, it will be seen that I have provided a coupling which differs very little 10 from the standard coupling employed in making sink connections and hence may be manufactured in an economic manner, since the additional material required for the lugs is so small as to be negligible. Other advantages may readily occur to those skilled 15 in the art to which this invention appertains.

I have illustrated in Figure 4 a type of faucet in which a threaded extension, such 20 as the portion 13 is not employed but in lieu thereof a threaded opening 24 is provided in the flanged end to receive the threaded extensions 25 of the elbow coupling 26. This type of faucet shown in 25 the drawing operates by means of the handle 27 swinging in a horizontal plane. This applies a lateral strain upon the faucet which is resisted by the provision of the horizontal lugs 23 formed upon said coupling. 30

While I have illustrated and described my invention with some degree of particu-

larity, I realize that in practice various alterations therein may be made. I therefore reserve the right and privilege of changing 35 the form of the details of construction or otherwise altering the arrangement of the correlated parts without departing from the spirit of the invention or the scope of the appended claims. 40

Having thus described my invention what I claim as new and desire to secure by United States Letters Patent is:—

1. A fitting comprising a coupling having a plurality of radial lugs, arranged diametrically opposite each other around its mouth and larger than the diameter of the body of the coupling and integral therewith and adapted to bear against the wall of the member to which it is to be attached at diametrically opposite points. 50

2. A fitting comprising an elbow coupling internally threaded to receive a pipe having a plurality of radial lugs arranged diametrically opposite each other around its mouth and larger than the diameter of the coupling and integral therewith and adapted to bear against the wall of the member to which it is to be attached. 55

In testimony whereof I affix my signature in presence of a witness.

GEORGE J. VON GLAHN. [L.S.]

Witness:

Wm. Zeaman.
